DESIGN FOR A FLOWER HOLDER

Mattie E. Perry, Orlando, Fla.

Application March 29, 1937, Serial No. 68,468

Term of patent 7 years

To all whom it may concern:

Be it known that I, Mattie E. Perry, a citizen of the United States, residing at Orlando, in the county of Orange and State of Florida, have invented a new, original, and ornamental Design for a Flower Holder, of which the following is a specification, reference being had to the accompanying drawing, forming part thereof.

In the drawing:

showing my new design.

I claim:

The ornamental design for a flower holder, as shown.

MATTIE E. PERRY.
